(57) **CLAIM**

The ornamental design for a car repair ramp as shown and described.

DESCRIPTION

FIG. 1 is a front, right, perspective view of a car repair ramp showing my new design;

FIG. 2 is a rear, left, perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a partially enlarged view of FIG. 10; and,

FIG. 10 is another partially enlarged view of FIG. 10.

The broken lines shown on the drawings depict portions of the car repair ramp that form no part of the claimed design.

1 Claim, 8 Drawing Sheets
